Filed Feb. 3, 1964, Ser. No. 78,480

Term of patent 14 years

(Cl. D61—1)

FIG. 2

FIG. 1

FIG. 3

FIG. 5

FIG. 4

FIG. 6

FIG. 7

FIG. 1 is a front elevational view of a tape reel latch showing my new design, in closed or latched condition; FIG. 2 is a left-side elevational view thereof;

FIG. 3 is a right-side elevational view thereof;

FIG. 4 is a view similar to that of FIG. 1 but showing the finger lever in open or unlatched condition;

FIG. 5 is a left-side elevational view thereof;

FIG. 6 is a right-side elevational view thereof; and

FIG. 7 is a rear elevational view thereof on a reduced scale.

The characteristic features of my design reside in the circular configuration of the whole and the U-shaped form of the finger lever.

I claim:

The ornamental design for a tape reel latch, substantially as shown and described.
